P. C. WILSON

TRAVELER SLIDE FOR SAIL ATTACHMENTS

Filed May 24, 1927

INVENTOR.
Prescott B. Wilson
BY
Willis Almon Anderson,
ATTORNEYS.

UNITED STATES PATENT OFFICE.

PRESCOTT C. WILSON, OF BROOKLYN, NEW YORK.

TRAVELER SLIDE FOR SAIL ATTACHMENTS.

Application filed May 24, 1927. Serial No. 193,775.

This invention relates to improvements in securing devices of the type wherein the element or part secured thereby is restrained for traveling movement along a certain course, and more particularly in some of its aspects the invention relates to improvements in traveling slides or runners for securing sails or the like for traveling movement along a spar or mast.

10 It is a general object of the invention to provide an improved securing device of the class mentioned so constructed and arranged as to diminish or practically avoid jamming or binding, or similar resistance to free traveling movement of the secured element.

15 A further and more particular object is to provide, in a sail securing device of the class mentioned, a runner or traveler slide having an improved anti-friction attachment where-
20 by jamming with the supporting guideway, or other objectionable resistance to move-
ment thereof, is effectively avoided during movement of the runner in either direction along the guideway, and under torsional and
25 other stresses exerted thereon by the sail in any possible direction.

20 A further object is to provide a sail securing device of the class mentioned having an improved anti-friction attaching arrange-
30 ment so as to permit free hoisting or lowering of the sail and operating to diminish the tendency to binding or jamming, thus to lessen the time and effort required to raise or lower the sail.

35 Other objects of the invention will be in part pointed out in the following detailed description of an illustrative but preferred embodiment of the invention, and will be in part obvious in connection therewith.

40 The invention accordingly comprises the features of construction, combination of elements, and arrangement of parts, which will be exemplified in the construction hereinafter set forth and the scope of the application of
45 which will be indicated in the claims.

For a more complete understanding of the nature and objects of the invention, reference is had to the following detailed description of the illustrative embodiment, and to the accompanying drawings, in which

50 Fig. 1 is a fragmentary elevation showing a sail secured to a mast by means of the improved attachment.

Fig. 2 is an enlarged perspective view

showing a traveler slide embodying the in- 55 vention.

Fig. 3 is a fragmentary elevation showing the traveler slide in position upon a guideway, parts being broken away to improve the disclosure. 60

Fig. 4 is a sectional plan of Fig. 3.

The service to which traveler slides em- 65 ployed in securing sails to masts, or the like, in sailing vessels, is exceptionally rigorous, and the tendency to binding and similar ob-
struction to free movement along the sup-
porting guideway is particularly great, due to the great variety of torsional stresses ex-
erted upon the slide in many different direc- 70 tions when the sail occupies different posi-
tions relatively to the mast. This binding
tendency is accentuated by the jerking and
slatting action in raising or lowering the
sails under rough weather conditions. It
will be obvious that, while the mast and slide 75
guiding attachment thereto remains in sta-
tionary position, the sail and attaching con-
nections therefor may be positioned at a
great variety of angles to the mast, and conse-
quently stresses upon the slide will be exerted 80
in numerous different directions in varying
degrees of torsion. The improved traveler
slide herein described is designed to avoid,
in a very large degree, the binding resistance
to free movement of the slide under the rigor- 85
ous service mentioned.

Referring to the drawing for a detailed 90 disclosure of the embodiment of the invention
there shown, a sail 10 of a sailing vessel
is supported by a spar or mast 11 which may
be positioned as desired. A guideway 12 in
the form of an elongated flat bar or plate is
secured to the mast by suitable securing de- 95
vices 13, its direction of length correspond-
ing generally with that of the mast. A sup-
porting block or strip 14 may be interposed
between the guide bar and the mast so as to
provide a firm seat for the bar and to space 100
it slightly from the adjacent surface of the
mast.

A plurality of traveler slides or runners 15 are mounted for slidable engagement with
the guideway in connected relation therewith, each runner being provided with an at-
taching bar 16 secured at longitudinally
spaced parts thereof to the runner as by studs
17. The attaching bar extends longitudinally 105
of the runner and is spaced slightly there-

from so as to provide an elongated slot or passageway for the reception of an attaching ring or link 18, which is thus movable longitudinally relatively to the runner, such movement being limited by the terminals of the slot, that is, by the studs 17. Each attaching link is connected to the sail in any desired manner, preferably including a reinforced eye 19 secured to the sail.

10 All of the runners 15 are of the same construction, and a description of one only is a description of all. As shown in Figs. 2 and 3, the runner is generally channel-shaped in cross section, including a back section 20, opposed side or edge sections 21 and opposed inwardly extending marginal projections or flanges 22. This construction provides opposed edge channels or grooves 23 for the reception of the edges of the guide bar, as shown in Fig. 4. The slide or runner is thus connected to the guide way for traveling movement in either direction therealong.

15 Anti-friction rollers 24 are mounted upon the runner, there preferably being two of these rollers at each side of the runner, spaced apart longitudinally a short distance. These rollers are positioned for engagement with the longitudinal edges of the guide bar 12, which is preferably provided with rounded 20 corners for presenting smooth contact surfaces with the anti-friction rollers. These rollers are preferably positioned wholly within the channels 23 of the runner and their axes are disposed transversely of the 25 channels and of the runner itself.

20 The contact faces of the rollers 24 may be formed in wide open channels substantially as shown in Fig. 4 and curved transversely of the contact edges of the guide bar; that is, the concave contact surfaces of the roller 25 are presented to the guide bar edges. The sides of the rollers adjacent the bar edges are preferably disposed within the channels 23 so that the bar edges when in operative 30 position may extend for a short distance into the runner channels 23.

35 By virtue of the open channel construction of the anti-friction rollers with the concave contact surfaces arranged as described, a certain amount of twisting movement of the runner is permitted before the guide bar edges come into contact with the respective roller surfaces. Torsional stresses upon the runner exerted by the sail are thus compensated 40 and the runner permitted to assume a non-binding position with reference to the guide bar no matter in what angular direction the pull of the sail is exerted upon the runner. It will be observed that the attaching bar 16 is 45 positioned intermediate the pairs of laterally disposed anti-friction rollers so that the torsional as well as other stresses imposed by the sail in different positions will be equally distributed to the runner, and through the rollers to the guide bar. By means of the ar-

50 range ment described friction and binding tendency are reduced to a negligible amount. It will be observed that the curvature or concave construction of the open channel contact surface of the rollers is so proportioned with reference to the width of guide bar 12 that the bar edges will contact with said surfaces toward the ends of the rollers to limit the twisting or torsional movement of the runner upon its longitudinal axis. The rollers, 55 therefore, always contact with the guide bar in all possible positions of the runner, and at no time is the guide bar permitted to come into contact with the walls of the channels 23.

60 The tendency to binding of the runner is still further diminished by the lost motion or automatic longitudinally adjusting connection between the sail and the runner provided by the elongated attaching bar 16, along which the connecting ring 18 is movable. By means of this adjusting connection longitudinal pulls upon the runner will always be exerted at the forward end thereof, thus helping to keep the runner in correct alignment 65 with reference to the guide bar.

70 Since certain changes may be made in the above construction, and different embodiments of the invention could be made without departing from the scope thereof, it is intended that all matter contained in the above 75 description or shown in the accompanying drawings, shall be interpreted as illustrative and not in a limiting sense.

75 It is also to be understood that the following claims are intended to cover all of the generic and specific features of the invention herein described, and all statements of the scope of the invention which, as a matter of language, might be said to fall therebetween.

80 Having described my invention, what I claim as new and desire to secure by Letters Patent, is:

85 1. In a device of the character described, in combination, an elongated guideway mounted upon a mast, or the like, a runner adapted to be attached to a sail, and means for attaching said runner to said guideway for movement therealong in opposite directions, said attaching means including a pair of rollers mounted at each side of said runner 90 and engaging said guideway at laterally spaced parts thereof, said rollers having wide open channels for receiving said guideways and permitting limited torsional or twisting movement of the runner relatively to the 95 guideway so as to reduce binding and friction.

100 2. In a device of the character described, in combination, an elongated guideway mounted upon a mast, or the like, and being in the form 105 of a flattened bar having its edge corners rounded, a runner adapted to be attached to a sail, and means for attaching said runner to said guideway for movement therealong in opposite directions, said attaching means 110

including a pair of rollers mounted at each side of said runner and engaging said guideway at the lateral edges thereof, said rollers having wide open channels for receiving the 5 guideway edges and having contact surfaces curved transversely of said edges.

3. In a device of the character described, in combination, an elongated guideway mounted upon a mast, or the like, a runner adapted to 10 be attached to a sail, and means for attaching said runner to said guideway for movement therealong in opposite directions, said attaching means including a pair of rollers mounted at each side of said runner and engaging said 15 guideway at laterally spaced parts thereof, said rollers having wide open channels for receiving said guideway and permitting limited torsional or twisting movement of the runner relatively to the guideway so as to 20 reduce binding and friction, and a longitudinally sliding sail connection positioned on said runner intermediate said pairs of anti-friction rollers.

4. In a device of the character described, in 25 combination, an elongated guideway mounted upon a mast, or the like, and being in the form of a flattened bar having its edge corners rounded, a runner adapted to be attached to a sail, and means for attaching said runner 30 to said guideway for movement therealong in opposite directions, said attaching means including a pair of rollers mounted at each side of said runner and engaging said guideway at the lateral edges thereof, said rollers 35 having wide open channels for receiving the guideway edges and having contact surfaces curved transversely of said edges, and a longitudinally sliding sail connection positioned on said runner intermediate said pairs of 40 anti-friction rollers.

5. In a device of the character described, in combination, an elongated guideway mounted upon a mast, or the like, a runner adapted to be attached to a sail and having 45 laterally disposed channels, and means for attaching said runner to said guideway for movement therealong in opposite directions, said attaching means including a pair of rollers mounted at each side of the runner in the 50 respective channel and engaging said guideway at laterally spaced parts thereof, said rollers having wide open channels for receiving said guideway for permitting limited torsional or twisting movement of the runner 55 relatively to the guideway.

6. In a device of the character described, in combination, an elongated guideway in the form of a flattened bar having its edge corners rounded, a sail attaching runner having 60 laterally opposed channels, and means for attaching said runner to said guideway for movement therealong in opposite directions, said attaching means including a pair of rollers mounted in each of the runner channels, 65 said rollers having wide open channels dis-

posed within the runner channels for receiving the edges of said guideway within said runner channels, and permitting limited torsional or twisting movement of the runner relatively to the guideway. 70

7. In a device of the character described, in combination, an elongated guideway mounted upon a mast, or the like, a sail attaching runner having laterally disposed channels, and means for attaching said runner to said guideway for movement therealong in opposite directions, said attaching means including a pair of rollers mounted at each side of the runner in the respective channel and engaging said guideway at laterally spaced parts thereof, said rollers having wide open channels for receiving said guideway for permitting limited torsional or twisting movement of the runner relatively to the guideway, and a longitudinally disposed 80 elongated attaching bar positioned on said runner intermediate said pairs of anti-friction rollers. 85

8. In a device of the character described, in combination, an elongated guideway in the form of a flattened bar having its edge corners rounded, a sail attaching runner having laterally opposed channels, and means for attaching said runner to said guideway for movement therealong in opposite directions, said attaching means including a roller mounted in each of the runner channels, said rollers having wide open channels disposed within the runner channels for receiving the edges of said guideway within said runner 90 channels, and permitting limited torsional or twisting movement of the runner relatively to the guideway, and a longitudinally slide- 95 able sail connection positioned on said runner intermediate said anti-friction rollers. 100

9. In a device of the character described, in combination, an elongated guideway in the form of a flattened bar, a sail attaching runner having laterally opposed channels, and means for attaching said runner to said guideway for movement therealong in opposite directions, said attaching means including a roller mounted in each of the runner channels and each having wide open peripheral channels disposed respectively within the runner 110 channels for receiving the edges of said guideway so as to permit limited twisting movement of the runner relatively to the guideway. 115

10. In a device of the character described, in combination, an elongated guideway in the form of a flattened bar, a sail attaching runner, and means for attaching said runner to said guideway for movement therealong in opposite directions, said attaching means including rollers mounted upon said runner and laterally disposed thereon, each of said rollers having a peripheral channel for receiving the adjacent edge of said bar and said channel being wide open relatively to the 120 125 130

thickness of the edge of said bar so as to permit limited twisting movement of the runner relatively to the guideway.

11. In a device of the character described, in combination, an elongated guideway in the form of a flattened bar, a sail attaching runner, and means for attaching said runner to said guideway for movement therealong in opposite directions, said attaching means including rollers mounted upon said runner and laterally disposed thereon, each of said

rollers having a peripheral channel for receiving the adjacent edge of said bar and said channel being wide open relatively to the thickness of the edge of said bar so as to permit twisting movement of the runner relatively to the guideway, the channels of said rollers having curved contact surfaces curved transversely of the adjacent edges of the said flattened bar.

In testimony whereof I affix my signature.
PRESCOTT C. WILSON.
